UNITED STATES PATENT OFFICE.

GEORGE J. WEGERER, OF BELL, CALIFORNIA, ASSIGNOR TO CALIFORNIA CYANIDE COMPANY, INCORPORATED, OF NEW YORK, N. Y., A CORPORATION OF DELAWARE.

FUMIGATING APPARATUS.

Application filed March 20, 1924. Serial No. 700,568.

This invention relates to fumigating apparatus and more particularly to improvements therein whereby the use thereof is safeguarded. The apparatus is particularly designed for handling dangerous liquids such as liquid hydrocyanic acid. It may be employed, however, in atomizing and vaporizing other and similar materials.

In fumigating vegetation, and particularly citrus trees, by means of liquid hydrocyanic acid, the trees are first enclosed in a cover or tent and the liquid is atomized and thus distributed through the enclosure. Apparatus has been devised whereby the liquid is forced under pressure through an atomizing nozzle which causes it to be finely divided so that it vaporizes quickly. In using such apparatus it is necessary to observe certain precautions because of the dangerous character of the liquid. It is particularly desirable to avoid leakage of the liquid from the atomizing nozzle while the apparatus is being transported from tree to tree and when the operator is not aware of the possibility of contact with the liquid or the vapor therefrom.

In certain apparatus heretofore used a check valve has been introduced at the nozzle so that the liquid escapes only when pressure is exerted thereon. There is, however, a slight amount of liquid in the nozzle and the pipe leading thereto, and the valve must close necessarily against the pressure exerted by this liquid. The resulting retardation of the valve action has permitted some liquid to escape after the apparatus should have been closed.

It is the object of the present invention to provide an improved apparatus in which the difficulty heretofore experienced is avoided, the valve being closed substantially instantaneously and without permitting the escape of any unvaporized liquid.

Further objects and advantages of the invention will be apparent as it is better understood by reference to the following specification and accompanying drawing which indicates in vertical section a portion of the apparatus embodying the improvements herein described and claimed.

The apparatus hereinbefore referred to is described in the application of Joseph D. Neuls, Serial No. 701,038, filed March 22, 1924, and includes in addition to the parts illustrated in the accompanying drawing a

receptacle for the liquid hydrocyanic acid or other fumigating agent and a device for selectively limiting the stroke of the pump plunger for the purpose of measuring the dose of the fumigating agent which is to be vaporized. That portion of the apparatus is not a part of the present invention and therefore need not be described herein with further detail.

The present invention includes the provision of means cooperating with the plunger or other device for applying pressure to the liquid to relieve the pressure thereon or to create a slight suction effect which will draw the liquid from the nozzle into the pipe connected therewith and assist the closing of the check valve in the nozzle. With this provision the cut-off is sharply defined and no liquid escapes after the plunger rod is released by the operator. This affords an important safeguard in the operation of fumigating apparatus by removing a danger to which the operators have been subjected heretofore.

Referring to the drawing, 5 indicates a pump cylinder to which the liquid flows from the receptacle (not shown). A plunger rod 6 is disposed in the cylinder and is loosely connected at its lower end to a piston 7. A guiding plunger 8 having a lubricating ring 9 is secured to the plunger rod above the piston. The loose connection between the plunger rod and the piston is afforded by a valve 10 which operates between the body of the piston and a cap 11 having openings 12 therein for the passage of liquid. The valve 10 closes a passage 13 when the plunger rod is in its lower position. When the rod is lifted to raise the piston the valve first opens to permit liquid to descend through the passage 13. Upon the downward movement of the plunger rod the valve first closes and then forces the piston 7 downwardly to apply pressure to the liquid in the cylinder. Suitable packing 14 is disposed about the piston and is held in place by a keeper 15 which is supported on a spring 16 bearing against a collar 17, the latter being threadedly secured to the lower end of the piston.

The pump is connected by a pipe 18 in which an outlet and a controlling valve 19 and 20 respectively are disposed to a nozzle 21 having an outlet 22. The valve 23 is supported in the nozzle and is normally held

by a spring 24 against a seat 25 so that liquid escapes from the pipe 18 only under the pressure applied by the piston 7.

In the bottom of the cylinder 5 I provide 5 a stop 26 having preferably a fibre seat 27 against which the end of the piston 7 is adapted to abut when the piston is in its lowermost position. A spring 28 surrounds the stop 26 and projects above it when the 10 piston 7 is raised. This spring is tensioned as the piston descends until it strikes the stop 26. The tension is sufficient to lift the piston off a short distance in the cylinder as soon as the operator releases the 15 plunger rod 6. This return movement of the piston 7 relieves the pressure on the liquid and creates a suction which draws the liquid from the nozzle into the pipe 18 as the valve 23 closes. Consequently the 20 valve does not have to operate against the back pressure of the liquid. The valve closes more quickly and the liquid which would remain otherwise in the nozzle is drawn into the pipe and retained there until the piston is again raised to draw a new 25 charge into the cylinder and then depressed to force the liquid from the cylinder and nozzle.

From the foregoing it will be observed 30 that my improvement is relatively simple. It nevertheless affords maximum protection to the operator and avoids accidental contact with the deadly liquid or vapors which are employed in fumigating. Practical use 35 has demonstrated the efficiency of the improved apparatus in preventing leakage of liquid or vapors therefrom during the handling of the fumigating apparatus.

Various changes may be made in the 40 form, arrangement and construction of the parts without departing from the invention or sacrificing any of the advantages thereof.

I claim:—

1. In a fumigating apparatus, the combination of a cylinder, a piston provided with 45 a valve within the cylinder, a nozzle connected to the cylinder and having an automatic valve therein to permit passage of a fluid therethrough under pressure, the piston being adapted to be moved through the cylinder with its valve in closed position to force fluid through the nozzle and adapted to be moved in reverse direction through the cylinder with its valve open to permit 50 fluid to flow from one side of the piston to the other and mechanism operable on the piston at the end of its pressure stroke to move the piston in the reverse direction before the valve therein is opened to thereby release the pressure on the fluid.

2. In a fumigating apparatus, the combination of a cylinder, a piston provided with a valve within the cylinder, a nozzle

connected to the cylinder and having an 65 automatic valve therein to permit passage of a fluid therethrough under pressure, the piston being adapted to be moved through the cylinder with its valve in closed position to force fluid through the nozzle and 70 adapted to be moved in reverse direction through the cylinder with the valve open to permit fluid to flow from one side of the piston to the other and mechanism operable on the piston at the end of its pressure 75 stroke to move the piston in the reverse direction before the valve therein is opened to thereby withdraw the fluid in the nozzle and to release the pressure exerted upon the valve in the nozzle. 80

3. In a fumigating apparatus, the combination of a cylinder, a piston provided with a valve within the cylinder and a nozzle connected to the cylinder by a pipe having an automatic valve therein to permit passage of a fluid therethrough under pressure, the piston being adapted to be moved through the cylinder with its valve in closed position to force fluid through the nozzle and adapted to be moved in the reverse direction through the cylinder with its valve in open position to permit fluid to flow from one side of the cylinder to the other side thereof and a spring for engaging the piston before the end of the pressure stroke 95 thereof, this spring acting upon the piston to move it in the reverse direction at the end of the pressure stroke and before the valve in the piston is opened to release the pressure exerted upon the nozzle valve by the 100 fluid in the pipe. 90

4. In a fumigating apparatus, the combination of a cylinder, a piston provided with a valve within the cylinder and a nozzle connected to the cylinder by a pipe having an automatic valve therein to permit passage of a fluid therethrough under pressure, the piston being adapted to be moved through the cylinder with its valve in closed position to force fluid through the nozzle and adapted to be moved in the reverse direction through the cylinder with its valve in open position to permit fluid to flow from one side of the cylinder to the other side thereof and a spring for engaging the piston before the end of the pressure stroke 105 thereof, this spring acting upon the piston to move it in the reverse direction at the end of the pressure stroke and before the valve in the piston is opened whereby the 110 fluid which is in the nozzle and beyond the nozzle valve is drawn back into the pipe and retained by the automatically closing nozzle valve. 115

In testimony whereof I affix my signature.

GEORGE J. WEGERER.
